(57) **CLAIM**

The ornamental design for a miter saw, as shown and described.

DESCRIPTION

FIG. 1 is a perspective view of an embodiment of a miter saw with a saw assembly disposed in a lower position.

FIG. 2 is a front elevational view of the embodiment of FIG. 1.

FIG. 3 is a rear elevational view of the embodiment of FIG. 1.

FIG. 4 is a left side elevational view of the embodiment of FIG. 1.

FIG. 5 is a right side elevational view of the embodiment of FIG. 1.

FIG. 6 is a top plan view of the embodiment of FIG. 1.

FIG. 7 is a bottom plan view of the embodiment of FIG. 1.

FIG. 8 is a perspective view of the embodiment of FIG. 1 with the saw assembly disposed in an upper position.

FIG. 9 is a front elevational view of the embodiment of FIG. 8.

FIG. 10 is a rear elevational view of the embodiment of FIG. 8.

FIG. 11 is a left side elevational view of the embodiment of FIG. 8.

FIG. 12 is a right side elevational view of the embodiment of FIG. 8.

FIG. 13 is a top plan view of the embodiment of FIG. 8; and, FIG. 14 is a bottom plan view of the embodiment of FIG. 8.
